(57) **CLAIM**

The ornamental design for a building block, as shown and described.

DESCRIPTION

FIG. 1 is a perspective view of a building block;
FIG. 2 is another perspective view thereof;
FIG. 3 is a front view thereof;
FIG. 4 is a right side view thereof, and which is identical to
left side view (not shown);
FIG. 5 is a top view thereof; and,
FIG. 6 is a perspective view of a building block being con-
nected together with other building blocks.
The features shown in broken lines form no part of the
claimed invention.
